UNITED STATES PATENT OFFICE

1,927,909

FURNACE WALL CONSTRUCTION

Philip Washington Antill, Ridgefield Park, N. J.,
assignor to American Arch Company, New
York, N. Y., a corporation of Delaware

Application December 6, 1926. Serial No. 152,768
Renewed July 23, 1930

42 Claims. (Cl. 72—101)

This invention relates to furnace wall construction, and particularly to unit or sectional walls.

One of the primary objects of the invention is the improvement of hollow furnace walls of the sectional type.

Another object of the invention is to provide such a wall of less difficulty of construction and repair, and, at the same time, greater stability and strength than those now commonly in use.

10 A further object is the provision of a wall construction of the character specified wherein the inner refractory portion shall be relieved of great stresses resulting from temperature variations or other causes.

15 Still another object is the direct utilization of the primary strength members of the outer or supporting wall portion in the supporting structure for the inner wall.

How the foregoing, together with such other advantages as are incident to my invention, or may occur to those skilled in the art, are obtained, will be clear from the following description of a preferred embodiment of the invention viewed in the light of the accompanying drawings

25 thereof, wherein—

Fig. 1 is an elevation of a portion of a wall section constructed in accordance with the present invention.

Fig. 2 is a plan view taken on the line 2—2 of Fig. 1, with the three upper rows of bricks removed; and

Fig. 3 is an enlarged view taken on the line 3—3 of Fig. 2, with certain parts broken away.

Referring, first, to Fig. 3, it will be seen that I have therein illustrated part of a hollow furnace wall having a solid or fixed outer portion 2, which may be of any suitable construction, and an inner refractory portion 3 supported therefrom, with an air space 4 between the two.

40 The inner wall 3 is built up of a vertical series of horizontally disposed units or sections, each of which is supported by a row of supporting castings or hanger members 5 (see Figs. 1 to 3). These hangers each have, at the head, a groove or slot 6, preferably re-enforced by laterally extending flanges 7, for direct engagement with the main structural work of the outer wall 2, such structural work being here shown as comprising horizontally disposed strength members or I-beams 8, although it will be understood that other forms of beams or like members may be used in the construction of the outer wall. Each hanger 5 has a pair of lateral flanges forming a cross-web 16, and carries at the bottom a foot 9, which together with the base of the main web 10 of the

hanger and the lateral bracket-like portions 11, forms a pair of pockets or recesses 12 adapted to support the lowermost bricks 13 of each wall section. The lower end of the hanger is adapted to bear at 14 against a shoulder 15 on the sub-jacent hanger.

Each wall section is built up on the supporting bricks or blocks 13, and comprises, in addition to said blocks, alternate rows or courses of tied and filler blocks 18, 18^a, and intermediate 65 blocks 17, respectively. That is, each course of intermediate blocks 17 lies between adjacent courses of tied and filler blocks 18, 18^a, the tied or secured blocks 18 being tied or supported laterally by the hangers 5 in a manner to be described. At the top of each wall section there is provided a row of L-shaped blocks 19 adapted to make a vertically sliding joint at 20 with the block 13 of the superjacent wall section, smaller blocks 21 and a sand or other seal 22 being provided in the gap between the L-blocks 19 and the blocks 18, 18^a, next above, as shown in Fig. 3.

By reference particularly to Figs. 2 and 3, it will be seen that the tied or secured blocks 18 are 80 secured as against lateral displacement by the tie members 23, 24, each of which has a pair of depending lugs 25 engaging sockets or vertical holes 26 in the ears 27 of the said bricks 18. The tie members or bars 23, which are alternated vertically with the ties 24, are of such a length as to engage the lateral webs 16 of adjacent hangers 5, and the shorter tie bars 24 are kept in their proper position and supported as against lateral displacement by the vertical rods 28, each of which extends through one vertical series of the alternating tie members 23, 24, and rests at the bottom upon one of the blocks 13. The tied or secured bricks 18 are recessed or shouldered at their rear outside edges, as shown at 29 in Fig. 95 2, while the filler blocks 18^a each have a similarly positioned boss or overhung edge portion 30 adapted to engage the shoulder of the adjacent secured brick, so that each pair of bricks 18^a are securely held by ship-lap joints with the adjacent brick 18 on either side.

Briefly reviewing the foregoing; it will be clear that each section of the refractory wall is built upon the brick 13 supported by the hangers 5, each row of brick 17 thereabove lying between 105 rows of secured brick 18 and filler brick 18^a arranged in pairs horizontally, vertically alternating pairs of the brick 18 being tied to the hangers 5, the other bricks 18 being merely tied together in pairs, with vertical rods 28 tying together the 110

vertically alternating tie members 23, 24, and the whole wall section being topped by the row of L-bricks 19 resting on the upper course of bricks 18, 18^a. Obviously, this construction provides an inner wall of maximum freedom for shifting movement relative to the supporting wall, to take care of expansion and contraction due to temperature changes, while, at the same time, maintaining proper lateral support and a solid foundation for the weight of each section, and permitting easy renewal of whole wall sections or parts thereof, or of the individual bricks or tie members therein. It has also the advantages of hollow wall construction, viz., the provision for circulating air therein, the preheating thereby of air for combustion, and the cooling and protection of the brickwork and the metallic members.

The metallic supporting and retaining structure, and particularly the hanger members and tie bars, considered per se, including various detailed features of their form and construction, are fully described and claimed in my copending divisional application, Serial No. 680,716, filed July 17th, 1933.

What I claim is:—

1. A furnace wall construction comprising in combination an outer supporting wall having supporting hangers, and an inner sectional refractory wall spaced therefrom and carried thereon by means of said hangers, each section of said refractory wall including supporting blocks carried directly by the hangers, and alternate courses of secured and filler blocks and of intermediate blocks, respectively, the secured blocks being secured to the hangers, the filler blocks engaging said secured blocks, and the intermediate blocks being positioned between courses of the secured and filler blocks.

2. A furnace wall construction comprising in combination an outer supporting wall having supporting hangers, and an inner sectional refractory wall spaced therefrom and carried thereon by means of said hangers, each section of said refractory wall including supporting blocks carried directly by the hangers, and alternate courses of secured and filler blocks and of intermediate blocks, respectively, said secured blocks being tied into the wall as against lateral displacement, said filler blocks engaging the secured blocks, and said intermediate blocks being positioned between courses of the secured and filler blocks.

3. A furnace wall construction comprising in combination an outer supporting wall having supporting hangers, and an inner sectional refractory wall spaced therefrom and carried thereon by means of said hangers, each section of said refractory wall including supporting blocks carried directly by the hangers, and alternate courses of tied and filler blocks and of intermediate blocks, respectively, said tied blocks being tied into the wall as against lateral displacement by means including tie members engaging said hangers, said filler blocks engaging the tied blocks, and said intermediate blocks being positioned between courses of the tied and filler blocks.

4. A furnace wall construction comprising in combination an outer supporting wall having supporting hangers, and an inner sectional refractory wall spaced therefrom and carried thereon by means of said hangers, each section of said refractory wall including supporting blocks carried directly by the hangers, and alternate courses of tied and filler blocks and of intermediate blocks, respectively, certain of said tied blocks each hav-

ing a hole therein and being secured as against lateral displacement by tie means comprising a member engaging said hole and two adjacent hangers, said filler blocks engaging the tied blocks, and said intermediate blocks being positioned between courses of the tied and filler blocks.

5. A furnace wall construction comprising in combination an outer supporting wall having supporting hangers, and an inner sectional refractory wall spaced therefrom and carried thereon by means of said hangers, each section of said refractory wall including supporting blocks carried directly by the hangers, and alternate courses of tied and filler blocks and of intermediate blocks, respectively, certain of said tied blocks each having a hole therein and being secured as against lateral displacement by tie means comprising a member engaging said hole and two adjacent hangers and certain other of said hung blocks each having a similar hole and being secured together in pairs by tie members each engaging the holes of a pair, said filler and intermediate blocks, respectively, spacing said tied blocks horizontally and vertically.

6. A furnace wall construction comprising in combination an outer supporting wall having supporting hangers, and an inner sectional refractory wall spaced therefrom and carried thereon by means of said hangers, each section of said refractory wall including supporting blocks carried directly by the hangers, and alternate courses of tied and filler blocks and of intermediate blocks, respectively, certain of said tied blocks each having a hole therein and being secured as against lateral displacement by tie means comprising a member engaging said hole and two adjacent hangers and certain other of said tied blocks each having a similar hole and being secured together in pairs by tie members each engaging the holes of a pair, together with means securing a group of the latter tie members from a group of the former tie members, said filler and intermediate blocks, respectively, spacing said tied blocks horizontally and vertically.

7. A furnace wall construction comprising in combination an outer supporting wall having supporting hangers, and an inner sectional refractory wall spaced therefrom and carried thereon by means of said hangers, each section of said refractory wall including supporting blocks carried directly by the hangers, and alternate courses of tied and filler blocks and of intermediate blocks, respectively, certain of said tied blocks each having a hole therein and being secured as against lateral displacement by tie means comprising a member engaging said hole and two adjacent hangers and certain other of said tied blocks each having a similar hole and being secured together in pairs by tie members each engaging the holes of a pair, together with means securing a group of the latter tie members from a group of the former tie members comprising vertical rods extending through holes in the vertically spaced tie members, said filler and intermediate blocks, respectively, spacing said tied blocks horizontally and vertically.

8. A furnace wall construction comprising in combination an outer supporting wall having supporting hangers, and an inner sectional refractory wall spaced therefrom and carried thereon by means of said hangers, each section of said refractory wall including supporting blocks carried directly by the hangers, and alternate courses of tied and filler blocks and of intermediate blocks, respectively, said tied and filler blocks being ar-

- ranged in horizontally alternating pairs, and said intermediate blocks spacing the courses of tied and filler blocks vertically. 9. A furnace wall construction comprising in combination an outer supporting wall having supporting hangers, and an inner sectional refractory wall spaced therefrom and carried thereon by means of said hangers, each section of said refractory wall including supporting blocks carried directly by the hangers, and alternate courses of tied and filler blocks and of intermediate blocks, respectively, said tied and filler blocks being arranged in horizontally alternating pairs with ship-lap joints between adjacent pairs and said intermediate blocks filling the spaces intermediate the courses of tied and filler blocks. 10. A furnace wall construction comprising in combination an outer supporting wall having supporting hangers, and an inner sectional refractory wall spaced therefrom and carried thereon by means of said hangers, each section of said refractory wall including supporting blocks carried directly by the hangers, and alternate courses of tied and filler blocks and of intermediate blocks, respectively, said tied and filler blocks being arranged in horizontally alternating pairs, together with tie members for the tied blocks, each tie member in every alternate row of tied and filler blocks engaging a pair of tied blocks, and each tie member in every other row of tied and filler blocks engaging a pair of tied blocks and a pair of hangers, and said intermediate blocks filling the spaces intermediate the courses of tied and filler blocks. 11. A furnace wall construction comprising in combination an outer supporting wall having supporting hangers, and an inner sectional refractory wall spaced therefrom and carried thereon by means of said hangers, each section of said refractory wall including supporting blocks carried directly by the hangers, and alternate courses of tied and filler blocks and of intermediate blocks, respectively, said tied and filler blocks being arranged in horizontally alternating pairs, together with tie members for the tied blocks, each tie member in every alternate row of tied and filler blocks engaging a pair of tied blocks, and each tie member in every other row of tied and filler blocks engaging a pair of tied blocks and a pair of hangers, together with a member engaging the alternating tie members of each vertical series of each section. 12. A furnace wall construction including in combination, a supporting structure, hangers carried thereby, a sectional refractory block wall, each section being carried on a plurality of hangers, and members engaging said hangers and blocks of the wall to secure the wall as against lateral displacement, each hanger having means of engagement with a subjacent hanger. 13. A furnace wall construction including in combination, a supporting structure, hangers carried thereby, a sectional refractory block wall, each section being carried on a plurality of hangers, and members engaging said hangers and blocks of the wall to secure the wall as against lateral displacement, there being ship-lap joints between blocks. 14. A furnace wall construction including in combination, a supporting structure, hangers carried thereby, a sectional refractory block wall carried on said hangers, and means securing said wall as against lateral displacement, one hanger being positioned at least in part by the next vertically adjacent hanger. 15. A furnace wall construction including in combination, a supporting structure, hangers carried thereby, a sectional refractory block wall carried on said hangers, and means securing said wall as against lateral displacement, vertically adjacent hangers being in substantially vertical alignment. 16. A furnace wall construction including in combination, a supporting structure, hangers carried thereby, a sectional refractory block wall carried on said hangers, and means securing said wall as against lateral displacement, each hanger having means of engagement with a subjacent hanger. 17. A wall construction including in combination, a supporting structure, hangers carried thereby and arranged in substantially vertically-extending aligned series, a sectional block wall carried on said hangers, each of said hangers being of substantially hook-formation adjacent one end for engagement with the supporting structure and having shelf means adjacent its opposite end for the support of blocks of the wall. 18. A furnace wall construction including in combination, a supporting structure, hangers carried thereby, a sectional refractory block wall carried on said hangers, and means securing said wall as against lateral displacement, each section of said refractory wall including a block carried by a pair of hangers and blocks supported on said block. 19. A furnace wall construction including in combination, a supporting structure, hangers carried thereby, a sectional refractory block wall carried on said hangers, and means securing said wall as against lateral displacement, each section of said refractory wall including a block carried by a pair of hangers and blocks supported on said block, the upper course of blocks of a section of the wall being relatively movably associated with blocks of the next superjacent section. 20. A wall construction including in combination, a supporting structure, hangers carried thereby and arranged in substantially vertically-extending aligned series and a sectional block wall carried on said hangers, the upper course of blocks of a section of the wall being relatively movably associated with blocks of the next superjacent section. 21. In a sectional furnace wall construction, a supporting structure, spaced-apart hangers supported thereby, a block extending between a pair of hangers and supported at its ends on said pair, a wall built up on said block composed of narrower blocks, and means tying certain of said narrower blocks to said hangers. 22. In a sectional furnace wall construction, a supporting structure, spaced-apart hangers supported thereby, a block extending between a pair of hangers and supported at its ends on said pair, a wall built up on said block composed of narrower blocks, and means tying certain of said narrower blocks in pairs to said hangers. 23. A furnace wall construction including in combination a supporting structure, hangers carried thereby, a sectional wall carried on said hangers, each section of said wall comprising support means including a continuous refractory block bridging the space between adjacent hangers and refractory blocks supported on said means, and means securing said wall as against lateral displacement, one hanger being positioned at least in part by the next vertically adjacent hanger. 80 85 90 95 100 105 110 115 120 125 130 135 140 145 150

lateral displacement and positioned to be shielded by the wall from the furnace chamber.

24. A furnace wall construction including in combination a supporting structure, generally upright support elements or hangers supported thereon, a sectional refractory block wall, and, for each section of the wall, support means extending between and carried on a plurality of said upright members or hangers, and members engaging said hangers and blocks of the wall to secure the wall against lateral displacement.

25. A furnace wall construction including in combination a supporting structure, upright supporting members or hangers carried thereby, a sectional refractory block wall, each section including groups of blocks, and each group receiving support from a plurality of hangers, and means retaining said wall against lateral displacement.

26. A refractory block for furnace walls having a rearwardly projecting eye adapted to be engaged by a retaining member for preventing horizontal displacement of the block toward the inside of the furnace and means upon a side face adapted to restrain movement of a horizontally adjacent block toward the inside of the furnace.

27. A refractory block for furnace walls having a rearwardly projecting eye adapted to be engaged by a retaining member for preventing horizontal displacement of the block toward the inside of the furnace, means upon a side face adapted to restrain movement of a horizontally adjacent block toward the inside of the furnace, and an opposite side face having a recessed portion adjacent the rear face of the block.

28. A refractory filler block for sectional furnace walls having laterally projecting means adjacent the rear of one side face thereof adapted to restrain movement of the block toward the inside of the furnace by engagement with a horizontally adjacent block and having an opposite side face recessed adjacent the rear thereof to a point out of contact with a co-operating adjoining block.

29. In a furnace wall construction, a supporting structure, spaced-apart hangers supported thereby, a wall of refractory blocks sectionally supported in belts or zones on said hangers, each section having courses of blocks in staggered relation, and complementary engaging irregularities on the faces of certain adjoining blocks of each section.

30. In a sectional furnace wall, a plurality of generally upright hanger members, each section being carried on a plurality of hangers, base blocks for each section substantially bridging the gap between adjacent hangers for the support of superposed courses of blocks, and for each section a series of blocks at the top of the section arranged to overlap the base blocks of the superjacent section.

31. In a furnace wall construction, an outer supporting structure including spaced-apart supporting members, an upright wall area of refractory blocks sectionally carried in belts or zones on said members for sectional weight support and sectional expansion and contraction, each belt or zone having means for securing blocks thereof to said members as against displacement laterally of the wall, and at least a certain course of blocks in each section or zone being in staggered or overlapping-joint relation to blocks of another course thereof.

32. In a furnace wall construction, an outer supporting structure including spaced-apart supporting members, an upright wall area of re-

fractory blocks sectionally carried in belts or zones on said members for sectional weight support and sectional expansion and contraction, each belt or zone having means for securing blocks thereof to said members as against displacement laterally of the wall, and complementary engaging irregularities on adjoining faces of certain adjoining blocks of a belt or zone, at least a certain course of blocks in each section or zone being in staggered or overlapping-joint relation to blocks of another course thereof.

33. In a furnace wall construction, an outer supporting structure, horizontally spaced-apart downwardly-extending hanger members suspended from said outer structure, an upright wall area of refractory blocks sectionally carried in belts or zones on said members for sectional weight support and sectional expansion and contraction, complementary engaging irregularities on adjacent faces of certain adjoining blocks of a zone or section, and means for retaining blocks of the zones or sections as against displacement laterally of the wall.

34. In a sectional wall construction, a supporting structure, hangers supported thereby superposed courses of blocks carried by the hangers, and tie members, said tie members engaging blocks to position them laterally and said blocks supporting the tie members to position them vertically.

35. In a sectional wall construction, a supporting structure, hangers supported thereby, superposed refractory blocks carried by the hangers, and tie members engaging a hanger and certain of said blocks to position the blocks laterally of the wall, the refractory blocks positioning the tie members in spaced relation vertically of the wall.

36. A sectional refractory furnace wall, means of independent support for each section at the outer side thereof, and a tie member slidably engaging an element of the support at its outer side and engaging and holding the refractory wall against said element at its inner side.

37. A sectional refractory furnace wall, means of independent support for each section at the outer side thereof, and a tie member slidably engaging the outer face of a portion of the support and having means engaging the refractory wall and holding it in fixed lateral relationship to said portion of the support, at the inner side of the supporting means.

38. In a furnace wall construction, an outer supporting structure including spaced-apart supporting members, an upright wall area of refractory blocks sectionally carried in belts or zones on said members for sectional weight support and sectional expansion and contraction, each belt or zone having means for securing blocks thereof to said members as against displacement laterally of the wall, and at least a certain course of blocks in each section or zone being in staggered or overlapping-joint relation to blocks of another course thereof, such belt or section comprising at least a lower course of blocks and an upper course of blocks resting thereon, and retaining means engaging blocks of such lower course as against inward and downward tilting of the latter under the weight of superposed blocks.

39. A furnace wall construction including in combination a supporting structure, upright supporting members or hangers carried thereby, a sectional refractory block wall, each section including groups of blocks, and each group receiv-

ing support from a plurality of hangers, and means retaining said wall against lateral displacement, such section comprising at least a lower course of blocks and an upper course of 5 blocks resting thereon, and gripping means engaging blocks of such lower course as against inward and downward tilting of the latter under the weight of superposed blocks.

40. In a refractory furnace wall having a plurality of vertically superimposed refractory wall sections independently supported for substantially independent vertical expansion and contraction of the sections, a section comprising a plurality of refractory blocks including a supporting block having an inner block supporting portion and an outer support engaging portion, and metallic support means for retaining the section in place comprising a portion providing a shelf engaging the lower face of the outer portion 15 of said supporting block for vertical support thereof, and a portion engaging the upper face of the outer portion of said supporting block to prevent tilting of the block under the influence of the weight supported by the inner portion 20 thereof.

41. In a sectionally supported refractory furnace wall, outer supporting structure and an inner refractory wall section supported for vertical expansion and contraction independently 25

30

of vertically adjacent sections and comprising a supporting block and a plurality of superimposed supported blocks, and means for supporting and retaining the section vertically and against displacement laterally of the wall comprising a portion carried by said outer structure and engaging a supporting block to provide vertical support, a second portion comprising vertically spaced-apart elements fixed against inward lateral displacement with respect to said outer structure and means for tying a plurality of the superimposed supported blocks against lateral displacement with respect to said elements comprising a rod engaging the latter and slidably removable with respect thereto to release said plurality of superimposed supported blocks.

42. In a refractory furnace wall comprising a plurality of vertically superimposed wall sections independently supported for independent vertical expansion and contraction, a section comprising a plurality of superimposed blocks including a supporting block, and cooperating supporting and retaining means for the section comprising a portion engaging a supporting block to provide vertical support and a portion comprising a vertically arranged rod adapted to secure a plurality of the supported blocks of the section against displacement laterally of the wall.
